UNITED STATES PATENT OFFICE.

GEORGE L. ARTZ, OF COLUMBUS, OHIO.

VEHICLE-SPRING.

SPECIFICATION forming part of Letters Patent No. 291,664, dated January 8, 1884.

Application filed September 17, 1883. (No model.)

To all whom it may concern:

Be it known that I, GEORGE L. ARTZ, a citizen of the United States, residing at Columbus, in the county of Franklin and State of 5 Ohio, have invented new and useful Improvements in Vehicle Springs, of which the following is a specification.

My spring is particularly adapted for side-bar vehicles; and it consists of four separate and 10 independent quarter-elliptic springs connected to a center bearing-plate in pairs, the upper short spring of each pair having its foundation upon the inner end of the lower short spring, and secured directly to it by the same 15 bolts and clips which secure the pair to the bearing-plate, thereby supporting the upper short springs directly upon the lower ones, and obtaining the full elasticity of every part of each spring, increasing the durability of 20 the spring as an entirety, while the superimposed relation of each pair forms practically a single spring, having its separate pairs arranged side by side, so that the width of the superimposed joined pairs is only the width 25 of two springs. This construction, while providing a foundation for the upper short springs directly upon the lower springs, gives the advantage of allowing each spring to be adjusted independently of each other 30 upon the bearing-plate to suit different widths of bodies and of running-gear, or side-bars set different distances apart; and this, so far as I know and can find, is a result due to the arrangement of my four separate and independent quarter-springs secured together in 35 pairs. A spring of three separate and independent parts has been used, in which a semi-elliptic spring has been arranged between two short top springs, each spring being separately bolted to a bearing-plate, side by side, so 40 that said plate has a width equal to that of the three springs, each short top, half-elliptic spring having its foundation upon the bearing-plate and not upon the lower mainspring; 45 but such construction, while giving greater elasticity than is obtained by two complete semi-elliptic springs, does not give the advantages and results of my spring.

Referring to the accompanying drawings, 50 Figure 1 represents a bottom view of a side-bar vehicle, showing my improved spring ap-

plied thereto; Fig. 2, a cross-section of the same; Fig. 3, a similar section, showing a modified arrangement of the springs upon their connecting-plate. Fig. 4 represents in 55 perspective my improved spring; Fig. 5, a similar view, the springs being arranged differently upon their connecting-plate. Fig. 6 shows the plate or plates to which the inner ends of the four springs are attached; and 60 Fig. 7 shows, in top, side, and bottom views, the manner of securing and bracing the four springs to their connecting-plate; and Fig. 8 the spring applied to a long connecting-plate shown in Fig. 6.

Springs consisting of an upper and a lower part have been united at the middle of their length, with their ends divergent, the upper spring supporting the body, and the lower one connected with the side bars; but in such 70 construction the full elasticity of either spring cannot be obtained, and moreover such spring is only adapted to fit vehicles having a certain width of body and distance between the side bars, and the springs therefore were required to be of the exact length to fit the vehicle; but as carriages are now largely manufactured in parts, and afterwards put together and finished for the trade, such springs cannot be generally used, and give much trouble 75 to the manufacturers in being fitted to bodies which vary greatly in width, while the running-gear side bars are generally made the same width apart. A spring of two sections connecting the side bars has been combined 80 with a rigid truss-bar for supporting the body, and with a plate for connecting the inner ends of said springs, so that they may be adjusted upon said plate to suit the width between the side bars, the said plates and the 85 inner ends of the springs being rigidly secured to the rigid truss-bar, thereby obtaining only a portion of the elasticity of the sectional springs. My improved spring, of four connected parts secured and braced together 90 in pairs at their inner ends, gives the full elasticity to each part, and can be readily adjusted and fitted to the gear and body parts of vehicles, thereby constituting a new article 95 of manufacture furnished the trade, adapted for adjustment to suit different widths of running-gear.

Referring more particularly to the construction of my spring, it will be seen from the drawings that the upper spring is in two separate parts or sections, A A', and the lower 5 spring is of two similar separate and distinct parts or sections, B B', having a length greater than the upper sections. These separate and distinct sections are secured together at their inner ends in pairs—one above the other—to a 10 plate, C, of steel or wrought iron, each section being formed of one, two, or more leaves. The upper leaves of the upper sections terminate in eyes at their outer ends, and are attached by clips D to the sill-bars of the body, while 15 the lower leaves of the lower springs terminate in eyes, and are attached by clips E and shackles F to the side bars of the running-gear. The springs thus united in pairs diverge at their outer ends in curved lines, and 20 they are secured together at their inner ends by bolts G, passing through coincident openings in the joining leaves and in the plate C, and fastened by a nut, H. Adjacent to such bolt-fastening, a clip, I, embraces the joining 25 leaves of the upper and lower springs and the plate C, close to their edges, and is firmly clamped thereto by a cross-bar, J, and nuts J', so as to brace the springs together upon each other, and to their connecting-plate and keep 30 them in line, the clip for this purpose being arranged between the fastening-bolt and the outer ends of the springs. The plate C is provided with perforations e, a suitable distance apart, into which the bolts G may be adjusted 35 when it is desired to adjust the springs in pairs in or out to suit the width of the body and the side bars, or to adjust the upper or the lower sections independently of each other, to suit the body, or to suit the side bars. For this purpose 40 the leaves of the springs may also be provided with additional perforations d. I prefer to use a plate having a width sufficient to allow the joining ends of each pair of springs to be fastened upon the plate side by side, so 45 that the ends pass each other with sufficient space between them to allow one leg of the bracing-clips to pass between them, as shown in Fig. 7. The springs, however, may be attached in pairs to each end of a narrow plate, 50 in line with each other, as shown in Fig. 5. The plate may be cut away to form end bearing parts, and thus use a long and wide plate, without diminishing the full elasticity of the springs, as shown in Fig. 6; or each pair of 55 springs may be secured to a separate plate, and the plates screwed upon a screw-stem, whereby the plates may be separately ad-

justed upon their screw-connecting stem to set the springs in or out, and the springs may be adjusted upon such separate plates. The 60 plate may be secured between the inner ends of the upper and lower spring-sections, or on their under sides, as shown, and the plate may be slotted. The springs may be of any suitable form. The springs consisting of the four 65 divergent separate sections, connected to a middle plate in pairs, renders the spring elastic throughout its length, and transfers the strain and weight from the plate-connection to the side-bar connections, and when the plate is 70 placed at the bottom of the springs, the separate lapping sections press against each other and yield to the load. The sections of the springs are adjusted upon their connecting-plate by loosening the clips and removing 75 the fastening-bolts, and the clip may be adjusted to suit the adjustment of the bolts G.

I claim—

1. The combination of the four separate and independent quarter-elliptic springs, A B, A' 80 B', connected together in pairs, the upper spring of each pair having its foundation upon the inner end of the lower spring, with a bearing, C, to which each pair is secured, substantially as described, for the purpose specified. 85

2. The combination, with the body and side bars of a vehicle, of a spring composed of four separate and independent quarter-elliptic springs connected together in pairs A B, A' B', the upper spring of each pair having its foundation upon the inner end of the lower spring, 90 the bearing-plate C, the clips I, and the bolts G, whereby each pair of superimposed springs is secured to allow for separate and independent adjustment of each spring of each pair, 95 substantially as described.

3. As a new manufacture, a vehicle-spring composed of four separate and independent quarter-elliptic springs connected together in pairs, the upper spring of each pair having 100 its foundation upon the inner end of the lower spring, a bearing-plate to which each pair of springs is separately secured in superimposed relation side by side, and suitable attachments, 105 whereby said separate pairs of springs are connected to the body and to the running-gear, substantially as described.

In testimony whereof I have hereunto set my hand in the presence of two subscribing witnesses.

GEORGE L. ARTZ.
